CAP REMOVER

Fred Mildner and John Slovak, Tarentum, Pa.

Application May 27, 1940, Serial No. 337,531

6 Claims. (Cl. 215—46)

Our invention relates to new and useful improvements in bottle cap removers.

An important object of our invention is to provide a remover that is adapted to be disposed interiorly of the crimped skirt portion of the bottle cap when the same is applied to the bottle and that includes an operating arm extending exteriorly of the cap and normally lying beside the neck of the bottle in a handy and unobstructing position.

Another object of our invention is to provide a remover of the above-mentioned character that includes means engageable with the skirt portion of the bottle cap to aid in the removal of the same from the bottle that is unique in its construction to prevent tearing or rupturing of the cap during its removal.

Still another object of our invention is the provision of a remover of the above-mentioned character that is always ready for use and that will dispense with the necessity of providing a separate tool to remove the cap from the bottle.

Yet another object of our invention is to provide a remover of the above-mentioned character that is simple in construction, inexpensive to manufacture and efficient and efficacious in the performance of its duties.

Other objects and advantages of our invention, will be apparent during the course of the following description.

In the drawing, forming a part of this specification, and in which like numerals are employed to designate like parts throughout the same,

Figure 1 is a side elevation of a device embodying our invention, illustrating the same associated with a bottle and bottle cap, and showing the same in the normal inoperative position.

Figure 2 is a view similar to Figure 1, but showing our device in the operative or cap removing position.

Figure 3 is a view similar to Figure 1, but showing the bottle and cap in cross-section.

Figure 4 is a perspective view of our device.

Figure 5 is a perspective view illustrating the manner in which our device is formed.

Figure 6 is a top plan view of a blank from which our device is fashioned.

Figure 7 is a top plan view of a blank for forming a modification of the invention, and

Figure 8 is a top plan view of a blank for forming still another modification of the invention.

In the accompanying drawing, wherein for the purpose of illustration, is shown a preferred embodiment of our invention, the numeral 10 designates a conventional bottle having a substantially cylindrical body portion 11 and upwardly tapering neck 12 which terminates in a beaded mouth 13. The conventional cap 14 is formed with a substantially circular top wall 15 having

a depending annular skirt 16 adapted to be crimped over the beaded edge of the mouth in the conventional manner. The liner 17, of cork, or the like, is disposed within the cap and in sealing relation with the open mouth of the bottle in the conventional manner.

Our device is associated with the cap and liner and is adapted to be applied to the bottle in the same operation with the application of the cap thereto. Figures 4, 5 and 6 illustrate one form of the invention wherein the tongue portion 18 terminates at one end in a circular head 19 of slightly lesser diameter than the inner diameter of the skirt 16 of the cap. The base 20, integrally connected to the other end of the tongue, is of substantially greater width than the tongue and is formed with forwardly extending tabs 21 and 22 spaced laterally of the tongue and terminating in close proximity to the peripheral edge of the head 19. Figure 6 illustrates the blank from which this form of the invention is formed and Figure 5 illustrates the manner in which the blank is fashioned into the finished device as illustrated in Figure 4. The sides 23 and 24 of the blank are rolled to bring the tabs 21 and 22 in overlapping relation with the tongue 18, and the rolled tabs are then arcuately bent in a direction away from the tongue to define the fulcrum points 25 and 26.

In operation, the enlarged head portion 19 is interposed between the inner face of the top wall 15 of the cap and the liner 17 and with the tongue 18 extending outwardly of the cap between the bottle and the skirt 16. The lever arm 27, formed by the rolling operation of the base 20, normally lies beside the neck of the bottle, as illustrated in Figure 1, and the fulcrum points 25 and 26 are disposed slightly below the rim of the skirt. When it is desired to remove the cap from the bottle the lever arm is moved upwardly, in the direction of the arrow in Figure 2, to bring the fulcrum points 25 and 26 into engagement with the outer face of the skirt 16. The fulcrum points will then cooperate with the tongue 18 to bend the portion of the skirt clamped therebetween and to roll the edge of the cap upwardly to disengage the same from the bottle.

In the form of the invention, as illustrated in Figure 7, the tongue 18 is formed with an enlarged semi-circular head portion 28 adapted to be positioned between the top 15 of the cap and the liner 17 in the manner described for the first form of the invention. The arcuate edges 29 and 30 of the head are adapted to bear against the inner face of the skirt 16 to hold the tongue against displacement. The blank 17 is fashioned into the finished cap remover in the manner described for the first form of the invention and the manner of operation to effect the removal

of the cap is so similar that no further explanation is thought to be necessary.

In the modification illustrated in Figure 8, the tongue 18 is not provided with the enlarged head portion described in the first forms of the invention. The tongue extends a substantial distance beyond the tabs 21 and 22 in a manner to traverse the inner face of the top portion 15 of the cap and with the distal end 31 thereof adjacent the inner face of the skirt at a point remote from the entrance of the tongue therein. The blank illustrated in Figure 8 is fashioned into the finished cap remover in the manner described in detail for the first form of the invention and the operation of the same for removing the cap from the bottle is so similar that no further explanation is thought to be necessary.

In the last form of the invention, the pressed relation between the tongue 18 and the cap provided by the capping machine during the application of the cap to the bottle is thought to provide a sufficient frictional engagement therebetween to prevent slippage of the tongue relative to the cap. In the first forms of the invention, the enlarged head portion of the tongue is provided as a safety factor in preventing sliding of the tongue relative to the cap when the fulcrum points 25 and 26 are moved into engagement with the skirt and leverage applied to the lever arm 27.

It is to be understood that the form of our invention, herewith shown and described, is to be taken as a preferred example of the same, and that various changes in the size, shape and arrangement of parts may be resorted to without departing from the spirit of our invention, or scope of the appended claims.

Having thus described our invention, we claim:

1. The combination with a bottle cap of the type formed with a crimped annular skirt and having an inner liner, of a cap remover comprising a tongue extending under the skirt and between the cap and liner; and a lever arm integral with the tongue and formed at each side thereof with rigid arcuately curved fulcrum tabs located at the juncture thereof with the tongue, the said tongue being bendable to bring the fulcrum tabs into engagement with the outer surface of the skirt portion of the cap at opposite sides of the tongue, and said fulcrum tabs cooperating with the tongue in rolling up the edge of the cap to disengage the same from a bottle when leverage is applied to the said lever arm.

2. The combination with a bottle cap of the type formed with a crimped annular skirt and having an inner liner, of a cap remover comprising a tongue extending under the skirt and between the cap and liner, said tongue terminating in an enlarged circular head portion of slightly lesser diameter than the inner diameter of the cap; and a lever arm integral with the tongue and formed at each side thereof with rigid arcuately curved fulcrum tabs located at the juncture thereof with the tongue, the said tongue being bendable to bring the fulcrum tabs into engagement with the outer surface of the skirt portion of the cap at opposite sides of the tongue, and said fulcrum tabs cooperating with the tongue in rolling up the edge of the cap to disengage the same from a bottle when leverage is applied to the said lever arm.

3. The combination with a bottle cap of the type formed with a crimped annular skirt and having an inner liner, of a cap remover comprising a tongue extending under the skirt and be-

tween the cap and liner, said tongue terminating in a semi-circular head portion the arcuate edges of which being adapted to engage the inner face of the skirt portion of the cap and to prevent displacement of the tongue relative to the cap; and a lever arm integral with the tongue and formed at each side thereof with rigid arcuately curved fulcrum tabs located at the juncture thereof with the tongue, the said tongue being bendable to bring the fulcrum tabs into engagement with the outer surface of the skirt portion of the cap at opposite sides of the tongue, and said fulcrum tabs cooperating with the tongue in rolling up the edge of the cap to disengage the same from a bottle when leverage is applied to the said lever arm.

4. The combination with a bottle cap of the type formed with a crimped annular skirt and having an inner liner, of a cap remover comprising a tongue extending under the skirt and between the cap and liner, said tongue being formed with an enlarged circular terminal end of slightly lesser diameter than the inner diameter of the cap; and a lever arm integral with the tongue and having portions disposed laterally of the tongue, the sides of the arm being rolled and the portions thereof laterally of the tongue being arcuately curved in a direction away from the tongue to define fulcrum points, the said tongue being bendable to bring the fulcrum points into engagement with the skirt portion of the cap, and said fulcrum points cooperating with the tongue in rolling up the edge of the cap to disengage the same from a bottle when leverage is applied to the said lever arm.

5. The combination with a bottle cap of the type formed with a crimped annular skirt and having an inner liner, of a cap remover comprising a tongue extending under the skirt portion of the cap and formed with an enlarged semi-circular terminal end positioned between the cap and liner, the arcuate edge of the terminal end being adapted to engage the inner face of the skirt to prevent displacement of the tongue; and a base portion integral with the tongue and formed with tabs spaced laterally of the tongue, the lateral sides of the base being rolled to define a substantially rigid lever arm and to position the tab portions above the tongue, the said tabs being arcuately curved in a direction away from the tongue and adapted to engage the skirt portion of the cap and to cooperate with the tongue in rolling up the edge of the cap to disengage the same from a bottle when sufficient leverage is applied to the lever arm.

6. A cap remover including a tongue terminating at one end in an enlarged portion adapted to be positioned within a bottle cap; and a base member integral with the other end of the tongue, said base being of substantially greater width than the tongue and including tab portions spaced laterally of the tongue the sides of the base member being rolled to define a substantially rigid lever arm and to position the tab portions above the tongue, the said tabs being arcuately bent in a direction away from the tongue to define fulcrum points, the tongue being bendable to bring the fulcrum points into engagement with a bottle cap, and said fulcrum points and tongue portion being mutually cooperative in rolling up the edge of the cap to disengage the same from a bottle.
